(57) **CLAIM**

The ornamental design for a jewelry product, as shown and described.

DESCRIPTION

FIG. 1 is a perspective view of a jewelry product; FIG. 2 is a top plan view thereof; FIG. 3 is a bottom plan view thereof; FIG. 4 is a left side elevational view thereof; FIG. 5 is a right side elevational view thereof; FIG. 6 is a front elevational view thereof; FIG. 7 is a rear elevational view thereof; and, FIG. 8 is a perspective view thereof showing the jewelry product on a hand. The broken line disclosure of the hand in FIG. 7 illustrates the environment. The remaining broken lines illustrate portions of the jewelry product. None of the broken lines forms part of the claimed design.
